UNITED STATES PATENT OFFICE.

EDWARD AUSTIN WATSON, OF ANDERSON, AND ROLLY J. FLOYD, OF GREENVILLE, SOUTH CAROLINA.

SPINNING MACHINE.

Application filed June 21, 1921. Serial No. 479,351.

To all whom it may concern:

Be it known that we, EDWARD AUSTIN WATSON and ROLLY J. FLOYD, citizens of the United States, residing, respectively, at 5 Anderson and Greenville, in the counties of Anderson and Greenville and State of South Carolina, have invented certain new and useful Improvements in Spinning Machines, of which the following is a specification.

10 The present invention relates to mechanism for operating the builder beams of spinning machines that control the ring rails, and this is in the nature of a modification of the structure disclosed in the patent 15 to Edward Austin Watson, No. 1,350,905, dated August 24, 1920.

The object of the present case is to provide an apparatus which may be in the form of an attachment that can be utilized on 20 a well-known form of beam, and will effectively control the short-stroke mechanism for said beam.

In the accompanying drawings:

Figure 1 is a view in elevation of a 25 builder beam and cams showing the improved mechanism in place.

Figure 2 is a cross sectional view.

Figure 3 is a view similar to Figure 2, but illustrating the arrangement of the parts 30 during the return of the plunger to its active position.

In the structure shown, the builder beam is designated 4 and the usual builder cam that operates thereon, is shown at 5. Secured to the cam 5 is a short-stroke cam 6, the two cams being mounted on a shaft 7. A bracket 8, fastened by a bolt 9, or other device, to the beam 4, has slidably mounted therein a transversely disposed 40 plunger 10 provided with a roller 11 that is adapted to engage and disengage the short-stroke cam 6. The outward movement of the plunger is limited by a stop pin 12 carried thereby and adapted to engage the 45 bracket 8.

Fixed to the shaft 7 is a worm 13 that is thus rotatable with the cams 5 and 6, and adjustably mounted on the plunger 10 by means of a collar 14 and set screw 15, is 50 an upstanding finger 17 having a terminal blade 18 adapted to engage with said worm. The outer end of the plunger is beveled as shown at 19, and located below and in the path of said beveled end when the plunger

is withdrawn, is a fixed cam 20 adjustably mounted in a supporting standard 21.

The operation of the device is as follows: When the roller 11 is engaged with the cam, as shown in Figure 2, the blade 18 will be engaged with the worm 13 and the depth 60 of this worm is sufficiently great to maintain said engagement within the limits of movement of the builder beam 4. Consequently it will be evident that as the cams rotate and the beam swings the plunger 10 will 65 be gradually withdrawn until the roller 11 is disengaged from the cam 6. The short stroke mechanism then becomes inactive and the cam 5 operates on the beam 4. When, however, the beam 4 is abnormally de- 70 pressed the outer beveled end 19 of the plunger will strike the cam 20, and said cam will cause a retrograde movement of the plunger, bringing the roller 11 beneath the cam 6 and in a position to engage the 75 same when the beam rises.

From the foregoing, it is thought that the construction, operation and many advantages of the herein described invention will be apparent to those skilled in the art, 80 without further description, and it will be understood that various changes in the sizes, shapes, proportion and minor details of construction may be resorted to without departing from the spirit or sacrificing any 85 of the advantages of the invention.

Having thus fully described our invention, what we claim as new, and desire to secure by Letters Patent, is:—

1. In apparatus of the character set forth, 90 the combination with a builder beam and a cam for operating it, of a reciprocatory device mounted on the beam and movable into and out of engagement with the cam, and co-axial means rotating with the cam 95 and directly engaging the device to move it out of engagement with the cam.

2. In apparatus of the character set forth, the combination with a builder beam and a cam for operating it, of a device mounted 100 on the beam and movable into and out of engagement with the cam, a co-axial worm rotating with the cam, and an element connected to the device and engaged with the worm to withdraw said device from the 105 cam.

3. In apparatus of the character set forth, the combination with a builder beam and a

cam for operating it, of a plunger slidably mounted on the beam and having a portion movable into and out of engagement with the cam, a co-axial worm rotating with the 5 cam, and an element connected to the plunger and engaged with the worm to withdraw said plunger from the cam.

4. In apparatus of the character set forth, the combination with a builder beam and 10 a cam for operating it, of a device mounted on the beam and movable into and out of engagement with the cam and cooperating with the cam to move the beam, means rotating with the cam for moving the device, 15 and means for effecting an automatic return of the device after its disengagement from the cam.

5. In apparatus of the character set forth, the combination with a builder beam and a 20 cam for operating it, of a device mounted on the beam and movable into and out of engagement with the cam, a worm rotating with the cam, an element connected to the device and engaged with the worm to

withdraw said device from the cam, and 25 means for automatically returning the device after its disengagement, when the beam is abnormally depressed.

6. In apparatus of the character set forth, the combination with a builder beam and a 30 cam for operating it, of a plunger slidably mounted on the beam and having a portion movable into and out of engagement with the cam, a worm rotating with the cam, an element connected to the plunger and engaged with the worm to withdraw 35 said plunger from the cam, and a fixed cam in the path of the plunger when the beam is abnormally depressed to return the plunger.

In testimony whereof, we affix our signatures in the presence of two witnesses.

EDWARD AUSTIN WATSON.
